DISPLAY HANGER

Edward E. Schaefer, River Forest, Ill.

Application February 5, 1957, Serial No. 44,753

Term of patent 3½ years

(Cl. D80—8)

Fig. 1 is a front elevational view of a display hanger, showing my new design;

Fig. 2 is a side elevational view thereof; and

Fig. 3 is a top plan view of Fig. 1.

I claim:

The ornamental design for a display hanger, substantially as shown.
